UNITED STATES PATENT OFFICE

2,252,813

SEAL

Cassianus Paoly, Belle Vernon, Pa.

Application October 5, 1939, Serial No. 298,130

1 Claim. (Cl. 229—78)

My invention relates to improvements in seals for use more particularly on envelopes and the like.

The invention is designed with the particular purpose in view of providing a lock tight seal which may be inexpensively applied to envelopes, files, packages, cartons and boxes for quickly and securely sealing the same without resorting to adhesive, and which is so constructed and arranged that tampering therewith may be easily detected.

To the accomplishment of the above, and subordinate objects presently appearing, a preferred embodiment of my invention, and one modification thereof, have been illustrated in the accompanying drawing, set forth in detail in the succeeding description, and defined in the claim appended thereto.

In the drawing:

Figure 1 is a view in rear elevation of an envelope embodying the preferred form of my invention,

Figure 2 is a similar fragmentary view of the closure flap and locking tab,

Figure 3 is a view in transverse section taken on the line 3—3 of Figure 1 and drawn to an enlarged scale,

Figure 4 is a view in vertical section taken on the line 4—4 of Figure 1, and

Figure 5 is a view in plan of a modification of the invention.

Referring to the drawing by numerals, in the preferred embodiment thereof, illustrated in Figures 1 to 4, my invention has been shown as applied to the usual envelope 1 having the body part 2 and a closure flap 3.

The seal of my invention, as illustrated in Figures 1 to 4, comprises a tongue-like locking tab 4 and a supplemental locking sleeve 5. The tab 4 has the form of a substantially rectangular elongated strip of any suitable semi-flexible material such as Celluloid, Cellophane, or the like, having a straight edge attaching portion 6 for attachment to the flap 3 as by a rivet 7, and a locking portion 8 adapted to project beyond the free edge of the flap 3 and provided with toothed, or serrated side edges 9 extending to the free end 10 of the strip. The teeth, or serrations, on the side edges 9 incline from the free end 10 of said strip.

The sleeve 5 is of flat, generally rectangular form, and of the same material as the tab 4 and is adapted to be attached to the body portion 2 of the envelope 1 with one open end facing the top edge of the envelope and in a position for insertion of the locking portion 8 of the tab 4 therein. Preferably for attaching the sleeve 5,

lugs 11 are provided at the corners thereof to receive rivets 12. Along the sides thereof the sleeve 5 is provided with internal teeth, or serrations, 13 fitting into the interstices between the teeth 13 of the side edges 9 of the tab 4 so that said teeth 13 and side edges 9 interlock and prevent withdrawal of the portion 8 from said sleeve. As will be understood, the teeth 13 and side edges 9 are arranged to provide a certain amount of clearance between the same whereby, and because of the semiflexibility of both the side edges 9 may wipe past said teeth 13 under insertion of the locking portion 8 in the sleeve 5, and said teeth and edges react with a snap action into interlocking engagement. Preferably the sleeve 5 is constructed with front and rear portions 14, 15 with spacing strips 16 interposed therebetween.

In the modification of the invention, shown in Figure 5, a series of locking tabs 17, similar to tabs 4 are provided in a strip assembly having tear-off or severing lines 18 thereon between said tabs. In this form of the invention the tabs 17 are designed to be numbered, lettered, or otherwise distinctively identified, for selective use in conjunction with the sleeve 5 so that in the event of tampering with the seal and attempted substitution of another tab, the tampering may be readily detected. The tabs 17 are designed more particularly for use in sealing such articles as meters before and after inspection.

The foregoing will, it is believed, suffice to impart a clear understanding of my invention without further explanation.

Manifestly, the invention as described, is susceptible of further modification than as disclosed and without departing from the inventive concept, and right is herein reserved to such other modifications as fall within the scope of the subjoined claim.

What I claim is:

A seal for attachment to an envelope having a body part and a closure flap comprising a strip-like male member, having an apertured end for riveting to said flap and a locking end for projection from said flap provided with saw toothed side edges, and a sleeve-like female member for attachment to said body part and insertion of the locking end of the male member thereinto, said female member having internal saw toothed sides for interlocking with the toothed side edges of said locking end, said toothed side edges and the teeth of said sides being semi-flexible for snap action interlocking under insertion of said locking part into the female part, the teeth of said edges and sides inclining oppositely to prevent retraction of the locking part.

CASSIANUS PAOLY.
